Application November 15, 1948, Serial No. 60,108
In Great Britain June 13, 1946

12 Claims. (Cl. 312—273)

1

This invention relates to cabinets for toilet articles, and while the invention will hereinafter be described with particular reference to its use as a cabinet for shaving articles or kits, it is to be expressly understood that it is within the contemplation of the invention to embody the same in cabinets for facilitating convenient access to other toilet articles. This application is a continuation-in-part of my applications Serial Nos. 600,741, filed June 21, 1945 and now abandoned and 681,348, filed July 3, 1946.

In my Patent No. 2,297,995, granted October 6, 1942, and reissued on March 14, 1944, Reissue No. 22,456, I have disclosed a cabinet wherein a door hinged at its lower edge is provided with rails or the like so that a shaving kit or kit-carrying means can be moved thereon from a position within the cabinet to a position exteriorly of the cabinet for ready use.

It is an object of this invention to provide an improved cabinet to facilitate access to toilet articles normally stored within the cabinet but movable to a stable position of ready access when a closure for the cabinet is opened.

Another object of my invention is to have the conventional medicine cabinet so constructed that the medicines will be segregated from the shaving and cosmetic articles and wherein there will be neat orderly storage for all articles.

Another object of this invention is to provide an improved device of the type characterized wherein the member for closing the cabinet also becomes a shelf extension in front of the toilet articles when moved to the exterior of the cabinet or partially to the exterior of the cabinet.

Another object of this invention is to provide an improved device of the type characterized wherein the movement of the toilet articles exteriorly or partially exteriorly of the cabinet may be effected automatically, as by movement of the closure member as an incident to the opening or release of the same.

Another object of this invention is to provide an improved device of the type characterized with which may be readily associated illumination means, as for example to facilitate shaving, or other electrical provisions, as for example a drying pad.

Another object of this invention is to provide an improved device of the type characterized which is simple in construction, durable in character, compact as to space consumption, and of such nature that it may be readily designed and adapted to take a wide variety of forms depending on the articles to be stored and to fit into

the architectural requirements of bathrooms or the like, having regard for the size, cost and appearance of the installation.

Other objects will appear as the description of the invention proceeds.

The invention is capable of receiving a variety of mechanical expressions, several of which are illustrated on the accompanying drawings, but it is to be expressly understood that the drawings are for purposes of illustration only, and are not intended to be a definition of the limits of the invention, reference being had to the appended claims for that purpose.

Referring in detail to the drawings, wherein 15 the same parts have corresponding reference characters in the several figures and different phases of the invention are illustrated more or less diagrammatically in different views for facility of understanding,

20 Fig. 1 is a perspective elevation of an embodiment of the present invention;

Figs. 2, 3 and 4 are vertical sections of the embodiment of Fig. 1 to illustrate respectively the cabinet in closed position, the cabinet when 25 the closure member is first opened and the cabinet when the toilet articles are moved further to the exterior of the cabinet;

Fig. 5 is a vertical section of the embodiment of Fig. 2 parallel to the face of the cabinet;

Fig. 6 is a perspective view of another embodiment of the present invention;

Figs. 7, 8 and 9 are vertical sections of the embodiment of Fig. 6 respectively illustrating the cabinet in closed position, the cabinet with closure members open and the cabinet with the toilet articles moved exteriorly of the cabinet;

Fig. 10 is a horizontal section of the embodiment of Fig. 6;

Fig. 11 is a front view of the embodiment of Fig. 6;

Fig. 12 is an enlarged view in section of the automatic means for moving the toilet articles exteriorly of the cabinet;

Fig. 13 is a perspective elevation of another embodiment of the present invention;

Fig. 14 is a vertical section through yet another embodiment of the present invention;

Fig. 15 is a front elevation of another embodiment of the present invention;

Fig. 16 is a perspective view from the rear of yet another embodiment and also showing the adapter hereinafter described;

Fig. 17 is a perspective of a detail of Fig. 13; 55 Figs. 18 and 19 respectively are elevational and

3

cross sectional views, the latter on line 19-19 of Fig. 18, of still another embodiment;

Fig. 20 is a section on the line 20-20 of Fig. 14.

In conformity with the present invention a cabinet 20 of any suitable size, construction and material is provided, having regard to the particular toilet articles, as a shaving kit, to be housed thereby. Said cabinet may be made an integral part of a usual medicine cabinet, or it may be made as a separate cabinet suitably recessed into the wall of the room, preferably immediately adjacent to and below the usual medicine cabinet, or it may be made as a separate portable cabinet that may be attached to a wall by any suitable support, or suspended from a wall in any suitable way, at any suitable location, as will be apparent to those skilled in the art.

Mounted within the cabinet 20 is a toilet kit or case 23 which also may be of any suitable size, construction and material and built to provide convenient access to any desired number of suitable toilet articles. As shown, the kit is in the form of a case having an open front and an open top and provided with one or more shelves 24, one or more drawers 25, suitable racks 26, etc., but it is to be expressly understood that the toilet cases shown have been selected merely for purposes of illustration.

Case 23 is suitably mounted so that it may move into and out of the cabinet 20 as hereinafter explained in greater detail. A variety of provisions for facilitating such movement are herein described, but it is to be expressly understood that they have been selected merely to exemplify some of the various provisions that may be used in embodying the invention, any suitable provision to this end being within the contemplation of this invention. Where economy or other reasons dictate the provision for the movement of the case into and out of the cabinet may be a single means disposed preferably in the central medial fore-and-aft plane of the cabinet as shown in Figs. 1 to 5, but for purposes of stability I may employ a plurality of runners disposed symmetrically with respect to the medial fore-and-aft plane of the cabinet as shown in embodiments herein illustrated.

To provide relatively slidable members in the embodiment of Figs. 1 to 5 the bottom 27 of the cabinet 20 has at opposite sides thereof a pair of fore-and-aft extending tracks or rails 28, here shown as in the form of inwardly facing channel-shaped ways in which slides a flat plate-like member 30 having at its opposite sides flanges 29 that fit slidably in the slots of said channel-shaped members 28. The bottom 22 of case 23 is secured in any suitable way as by screws to the member 30. To provide relatively slidable members in the embodiment of Figs. 13 and 17 the ways for the runners are shown as in the form of inverted T-shaped slots 31 provided in a flat plate 32 suitably secured to the bottom of the cabinet, while the underside of the case 23 is provided with a pair of plates 33 suitably attached to the bottom 22 of the case as by screws 34 and having an inverted T-shaped rib or runner 35 of any suitable length sliding therein. In the embodiment of Figs. 14 and 20 a lazy tongs or set of nested links 36 is suitably attached to the bottom 22 of the case 23 at 37 and directly to the cabinet wall, preferably the bottom 27 thereof, at 38. The relatively slidable members of the embodiment of Fig. 15 include a plate 39 suitably attached to the bottom 22 of the case 23 and it in

4

turn slides by means of the dovetailed runners 40 in the dovetailed grooves 41 of a second plate 42 which may be either fixedly attached to the bottom 27 of the cabinet 20 or it may itself be slidable so as to double the extent of the projection of the case outside of the cabinet, in which event the lateral edges of the plate 42 may be provided with slotted plates 43 for cooperation with pins 44 mounted in the lateral walls of the cabinet 20 and projecting into the slots of said plates 43. The relatively slidable members of the embodiment of Fig. 16 include a plate 45 provided for attachment to the bottom of the case and it carries suitable brackets 46 for slidable movement on a pair of rods, bars or the like 47 of any suitable cross section. Such rods, bars or the like may be directly attached to the bottom 27 of the cabinet or to the rear wall thereof at their inner extremities. Other suitable means to provide for the sliding of the case 23 into and out of the cabinet 20 will now be apparent to those skilled in the art.

In the several embodiments means (not shown) are provided to constitute stops to prevent movement of the case so far out of the cabinet as to result in a disengagement of the case from the cabinet by separation of the members in sliding engagement. Such stops may conveniently be associated with the ways or runners or they may be mounted in the cabinet walls for cooperation with the slidable parts.

Where the slidable member has ledges running in channel-shaped grooves or the runners are of wedge or inverted T-shape and they are stopped before disengagement from the grooves in the tracks or rails the case is still firmly supported and stable when moved to its forwardmost position, but to relieve the runners and tracks from sustaining the overhanging weight of the forwardly disposed case, and particularly where the case is extended to a considerable distance in front of the cabinet so that the moment of the case is relatively large, means may be provided for cooperation with the slidable support to oppose the moment of the extended case tending to rotate the same around the edge of the cabinet. Thus as shown in Fig. 15 suitable guide members 48 may be attached to the side walls of the cabinet and overlay the upper surface of the slide 42 to hold the latter against tilting movement. Also any suitable antifriction means may be provided between the relatively slidable elements of the support.

In conformity with the present invention the movement of the case forwardly may be effected by movement of the closure member of the cabinet, or it may be effected automatically by the opening or release of the closure means, or it may be effected manually by operation of the closure means.

In the embodiment of Figs. 1 to 5 the door 50 for closing the front of the cabinet is shown as hinged at 51 to the lower edge of the case 23. The lower extremity of the door 50 extends beyond the hinge 51 as shown at 52, so that when the door is opened this extension 52 engages the forward ends of the channel-shaped ways 28 as abutments and thereby cams the door, together with the plate-like member 30 to which it is hinged and the case 23 mounted on the latter, to a forward position. If, as shown, in Fig. 2, the front of the door 50 is to be flush with the face of the cabinet, the forward ends of the channel-shaped members 28 are set back from the face of the cabinet by an amount equal to the thickness of

the door, and the front extremity of the bottom 27 of the cabinet 20 is suitably grooved as shown at 53 so as to provide for the aforesaid movement of the extension 52. By varying the elevation of the hinge line above the bottom 27 of the cabinet, and thereby the length of the extension 52, as well as the location of the abutments for cooperation with the latter, the extent to which the case 23 is cammed forwardly by the opening movement of the door can be varied so as to predetermine the extent to which the case 23 is moved forwardly with respect to the cabinet. With the arrangement shown in Figs. 1 to 5 the case 23, as shown in Fig. 3, is cammed forwardly by the opening movement of the door so as to advance the case 23, with the parts carried thereby, forwardly of the position occupied by the shelves of the ordinary medicine cabinet, but projecting out of the cabinet only to a small extent, as this is ordinarily sufficient to dispose the parts carried by the face 23 in a position of ready accessibility.

When the door is in its lower horizontal position the extension 52 engages the bottom of the case and holds the door in a horizontal position so that it constitutes a shelf projecting forwardly from the case. If it is then desired to advance the case 23 so that it projects to a greater distance from the cabinet 23, the door 50 may be pulled outwardly, advancing the member 30 and the case 23 carried thereby up to the limit predetermined by the stop means hereinabove referred to, to the position shown in Fig. 4.

When the door is in its closed position as shown in Fig. 2 it completely closes the front of the cabinet, and any suitable spring lock as diagrammatically indicated at 54 may hold the door closed, the lock preferably being of the type well known in cabinet constructions that is readily releasable when a moderate pull is applied to the knob 55. Movement of the door 50 to open position, as shown in Fig. 3, automatically advances the case 23 forwardly to a position of ready accessibility and to an extent determined by the length of the extension 52 of the door below the hinge 51. If preferred, the hinge 51 may be a spring hinge so as to cause the door to move to this position automatically. If desired the case 23 can then be moved still farther out of the cabinet 20 to the position shown in Fig. 4, as explained above. In either open position of the door 50 it constitutes an extension shelf which may be used for deposit of the shaving or other toilet articles while in use. Pushing inwardly on the door 50 moves the case from the position of Fig. 4 to that of Fig. 3, whereupon the door 50 may be swung upwardly to move the case back into the cabinet and close the front of the latter.

This same automatic camming of the case forwardly due to the opening movement of the door may also be employed when other provisions are used for mounting the case for movement into and out of the cabinet as hereinabove referred to. Thus in the embodiment of Fig. 14 wherein the case is movably mounted by lazy tongs or a set of nested links, the door may be hinged to the bottom of the case 23 as shown at 51 and the lower extending projection 52 of the door may cooperate with blocks 86 secured in any suitable way at opposite extremities of the bottom 27 of the cabinet 20, so as to provide abutments for cooperation with the door extension 52 and effect the camming action when the door is opened. Similarly, in the embodiment of Fig. 13 the door (not shown) may be hinged to the bot-

tom 22 of the case 23 as shown at 51 and the extending portion 52 of said door (compare Figs. 1-5) cooperates with the forward edge of the plate 32, the latter acting as an abutment to effect the forward camming action of the case. In the embodiment of Fig. 15 the door (not shown) may be hinged at 51 on the plate 39, and the forward edge of the second slideable plate 42 acts as an abutment while the door is being opened for cooperation with the extension 52 (compare Figs. 1-5) in effecting forward movement of the member 39 together with the case 23 carried thereby with respect to the lower plate 42.

The embodiment of Figs. 6 to 12 illustrates an automatic construction employing the type of case and means providing movement thereof into and out of the cabinet of the type embodied in Figs. 1 to 5, but it is to be expressly understood that the automatic feature may be associated with the other embodiments illustrated or other suitable constructions within the present invention. In this form the front of the cabinet 20 is shown as provided with closure means composed of two leaves 56 and 57 hinged respectively at 58 and 59 to the upper front edge of the cabinet 20 and to the lower front edge of the case 23. In this embodiment the closure member for actuating the automatic means is one of the two leaves, preferably the lower. The hinges 58 and 59 are preferably spring hinges so that the leaves when released will move automatically to upper and lower horizontal positions as shown in Fig. 8. Any suitable lock releasable mechanically or electrically as diagrammatically indicated at 60 in Fig. 7 may be used for retaining the doors in closed position, or the lock may be one such as referred to in conjunction with the embodiment of Figs. 1 to 5 with reliance on the spring hinges to move the leaves 56 and 57 to upper and lower horizontal positions to effect the automatic operation next to be described.

To move the case to its forward position automatically, suitable spring means are provided interiorly of the cabinet for cooperation with the case or some movable part attached thereto for projecting the case to its forward position when actuated by the lower leaf 57 moving to its horizontal position. Any suitable means to this end may be employed. The embodiment of Figs. 6 to 12 employs a pair of spring actuated devices 61 symmetrically arranged with respect to the fore-and-aft medial plane of the cabinet. As shown in enlarged sectional detail in Fig. 12, each spring actuated device 61 includes an outer cylinder 62 attached in any suitable way to the bottom 27 of the cabinet 20. Telescopically movable in said cylinder 62 is a plunger 63 attached by suitable brackets 64 to the underside of the case 23. Pivotally mounted on a pin 65 carried by and extending diametrically across the cylinder 62 is a trigger 66 having a forwardly projecting trip arm 67, the trip arms of the two devices 61 being connected as shown at 68 for simultaneous operation. Trigger 66 has a forwardly extending detent arm 69 provided with a nose 70 adapted to engage and lock with the extremity of a slot 71 in the cylinder 62 and thereby form a latch for the plunger in its inner position. Interposed between the trigger 66 and the front end of the plunger 63 is a coil spring 72 centered by a lug 73 at the forward end of the plunger and by a lug 74 on the trigger 66. Plunger 63 is slotted as shown at 75 so that it may move with respect to the transversely extending pivot pin 65. Trip member 67, 68 projects

forwardly to a position where it is engaged by the lowermost extremity of door leaf 57 as it moves into its horizontal position shown in Fig. 8. Trigger 66 is thereby moved slightly in an anti-clockwise direction sufficiently to release the latch by freeing the nose 70 on the detent arm 69 from its slot 71, whereupon the spring 72 moves the plunger 63 to its forwardmost position carrying the case 23 therewith by reason of the brackets 64. Thus the case 23 is moved automatically to the position shown in Fig. 6 by the action of the spring hinge moving door leaf 51 to its horizontal position shown in Fig. 8. To close the cabinet the leaf 57 is pushed rearwardly against the tension of the springs 72 until the plungers are locked in inner position by the operation of the latches 70, after which the leaves of the door may be moved to closed position and locked there by the lock at 60.

The embodiment of Figs. 6 to 12 also illustrates an additional feature that may be incorporated in this and other embodiments of the present invention: the upper leaf 56 of the door is shown as provided with any suitable lighting means 76, with or without a suitable reflector, and said lighting means preferably is automatically energized by one of the two leaves here shown as the upper leaf 58 closing a switch through a press button 77 as the upper leaf 56 is moved automatically to its open position by its spring hinge 58.

The embodiments of Figs. 13, 15, 16 and 17 illustrate how cases of different sizes may be readily adapted for use with the present invention. As here shown the case 23 is attached to its slidable support by an extension bracket 78 composed of a pair of relatively slidable members 79 and 80 (see Figs. 16 and 17) having upstanding flanges 82 by which the adapter constituted by this extension bracket 78 may be attached to the sides of the case as shown at 83 in Figs. 13 and 15. By telescoping the plates 79 and 80 with respect to each other they can be adjusted in the direction of the width of the cabinet so as to receive cases of different widths. The slidable means being properly located and attached to the adjustable plates the bottom of the case may then be attached to the adapter, Fig. 15 showing the adapter attached to the slidable plate 39 by screws 84. The embodiments of Figs. 13 to 16 may be made fully automatic if desired by providing the same with spring actuated plungers tripped by the movement of the door to open position.

Another embodiment of the invention is illustrated in Figs. 18 and 19 wherein the case for movement into and out of the cabinet occupies only a part of the space available for the arrangement of shaving articles, toilet articles or the like, the construction here illustrated being of the type disclosed and claimed in my application Serial No. 681,348, filed July 3, 1946, wherein the cabinet is provided with suitably arranged hingedly mounted partitions, shelves, and the like so as to increase the flexibility with which the interior of the cabinet may be subdivided into compartments of varying shapes, sizes and locations to meet the desires of the user. The cabinet 90 as illustrated is provided with a pair of vertical partition members 91 and 92 hingedly mounted at 93 and 94 on the rear wall 95 of said cabinet so that they may be folded back against said rear wall or moved forwardly to a right angular position wherein the width of the cabinet is subdivided into three compartments arranged widthwise of the cabinet. As illustrated, these compartments are arranged symmetrically width-

wise of the cabinet, but this is not necessary. Partition member 92 and end wall 96 are shown as carrying shelves 97 and 98 hingedly mounted at 99 and 100 so that they may be folded against the vertically extending member on which they are mounted or moved to horizontal position to constitute a shelf, in which position the two members 98, 99 may be in alignment or arranged to provide non-aligning shelves. The compartment at the opposite extremity of the cabinet is shown as provided with one or more drawers 101.

Case 103 in this embodiment of the invention is moved into and out of the central compartment 102 of the cabinet by the opening and closing movements of the door. Case 103 may be of such a depth as to occupy the full depth of the compartment 102, or as illustrated it may be shallower than the compartment so as to provide space at the rear thereof in which bottles or the like 104 may be disposed. Case 103 may be of any suitable construction, being shown as in the form of an open faced kit, box or comparable container carrying on its rear wall a plurality of hooks, clamps or the like 105, mounted in any suitable way so that various shaving, toilet or the like articles may be mounted or suspended thereon in position for ready accessibility.

The cabinet 90 is provided with a suitable closure member or door 106 hinged to the lower edge 30 of the cabinet by suitable horizontal hinges 107 so that it may be moved into a horizontal position forming an extension of the bottom of the cabinet and providing a shelf that projects forwardly of the cabinet for the convenient support of toilet articles when in use. Any suitable construction 35 may be used for holding the closure member firmly in its horizontal position, that shown being composed, at each side of the closure member, of a pair of links 107 and 108 pivoted together at 109 and pivoted to the closure member and the end wall of the cabinet at 110 and 111, respectively. Closure member 106 may also be provided with any suitable locking element 112 for retaining the closure member in closed position 40 in a manner well understood in the art.

In conformity with the present invention case 103 moves forwardly into a position of ready accessibility due to the opening movement of the door. To this end, case 103 is shown as supported 45 at either side thereof by a series of interconnected pivoted links 114 attached to the side of the case at one extremity as shown at 115 and attached at its opposite extremity to the closure member 106 as shown at 116. When the closure member 106 is in closed position as shown in full lines in Fig. 18 the case is supported in the central compartment 102 of the cabinet, but forwardly of the rear wall thereof as before referred to. The bottom of the case is then supported above the bottom of the cabinet, providing a free space underneath the case which is also available for use. When closure member 106 moves from closed to open position as indicated 50 by dotted lines in Figs. 18 and 19, the links are so constructed as to pull the case forwardly out of the cabinet in vertical position as shown at 117 in Fig. 18 and then, if desired, the links may be so constructed that they will lower the case onto the closure member 106 as shown at 118 in Fig. 18. Conversely, when closure member 106 is swung 55 upwardly around its hinge 107 the case 103, by reason of the construction of the links 114, is first raised and then moves inwardly into its compartment 102 as shown in Fig. 18 in full lines. 60

75 It will therefore be perceived that by the pres-

ent invention a cabinet for toilet articles has been provided which is of wide utility and readily adaptable to a wide variety of conditions and services. In each embodiment relatively movable parts which may take a variety of forms and which are preferably relatively slidable members provide for movement of the case containing the toilet articles to a forward position for ready access, and if desired the extent of movement which may be nearly as great as the depth of the cabinet to dispose the case in front of the cabinet. By providing one or more intermediate parts between the relatively movable members attached to the case and to the cabinet as in Fig. 15 the extent of forward movement of the case may be made appreciably greater. At the same time the closure member for the cabinet in its entirety or a leaf thereof may be used as an extension shelf in front of the case, providing a convenient platform upon which to place the toilet articles while in use. By hinging the door or a leaf of the door to the case, the entire door or leaf is free for use as a shelf, and at the same time the door or leaf may be used to effect the movement of the door outwardly and also as a push-pull member for moving the case into and out of the cabinet. While the preferred embodiments use relative sliding motion between the case and cabinet a hinged or other pivotal movement between the case and the cabinet may be used with certain aspects of the present invention. Furthermore, the present invention readily lends itself to fully automatic operation so that by merely pressing a suitable button the door or door leaves may be readily released, whereupon the door or door leaves under the action of their spring hinges move to their outer position of service automatically and, in so doing, actuate automatic means for moving the case outwardly, closing the switch to energize illuminating means, etc. Furthermore, each of the constructions provides a relatively simple and compact arrangement which is strong and durable with the case for the toilet articles supported rigidly in a position of stability when moved to its position of service.

While the embodiments of the invention illustrated on the drawings have been described with considerable particularity, it is to be expressly understood that the invention is not limited thereto as the invention is capable of receiving a variety of other expressions as will now be apparent to those skilled in the art, while changes may be made in the details of construction, arrangement, proportion of parts, etc., and certain features may be used without other features, and the several features disclosed may be associated in various combinations thereof, all without departing from the spirit of the present invention.

What is claimed is:

1. A cabinet for articles, comprising an outer cabinet, a case for said articles housed in said outer cabinet, relatively movable members attached to said case and said outer cabinet for movably mounting said case to move into and out of said outer cabinet and to provide a rigid support for said case when in its outer position, and a closure member for said outer cabinet pivotally attached to said case and operable to move said case into and out of said cabinet.

2. A cabinet as defined in claim 1 in which said closure member is hinged to the lower horizontal edge of said case to form a shelf in front of said case when in open position.
3. A cabinet as defined in claim 1 in which means are provided and actuated by said closure member upon reaching the open position for automatically moving said case out of said cabinet.
4. A cabinet as defined in claim 1 wherein relatively slidable members attached to said case and said outer cabinet prevent disengagement thereof.
5. A cabinet as defined in claim 1 in which said closure member comprises upper and lower portions, said lower portion being pivoted to said case, said upper portion being pivoted to said outer cabinet and pivoting upwardly, said upper and lower portions of said closure member being movable to open position.
10. A cabinet as defined in claim 1 in which said movable members associated with said case are provided with an adjustable adaptor for operative connection to cases of different sizes within said cabinet.
15. A cabinet as defined in claim 1 in which pivotally connected links are attached at their opposite ends to said case and to a wall of said outer cabinet.
20. A cabinet as defined in claim 1 wherein the means operated by the movement of said closure member comprises pivotally connected means operatively connected at their opposite ends to said case and to said closure member.
25. A cabinet comprising an outer cabinet, a case housed in said outer cabinet, relatively movable members attached to said case and said outer cabinet for movably mounting said case to move into and out of said outer cabinet and to provide a rigid support for said case when in its outer position, and a closure member for said outer cabinet pivotally attached to said case, the hinged end of said closure member engaging a wall of said outer cabinet to act as a cam to move said case forwardly when said closure member is moved to open position.
30. A cabinet as defined in claim 9 in which said closure member extends below said case and engages a wall of said outer cabinet to act as a cam to move said case forwardly when said closure member is moved to open position.
35. A cabinet as defined in claim 9 in which means are provided and actuated by said closure member upon reaching the open position for automatically moving said case out of said cabinet.
40. A cabinet as defined in claim 9 in which said closure member when in open position comprises a push-pull means for moving said case into and out of said cabinet.
45. A cabinet as defined in claim 9 in which means are provided and actuated by said closure member upon reaching the open position for automatically moving said case out of said cabinet.
50. A cabinet as defined in claim 9 in which said closure member extends below said case and engages a wall of said outer cabinet to act as a cam to move said case forwardly when said closure member is moved to open position.
55. A cabinet as defined in claim 9 in which means are provided and actuated by said closure member upon reaching the open position for automatically moving said case out of said cabinet.
60. A cabinet as defined in claim 9 in which said closure member when in open position comprises a push-pull means for moving said case into and out of said cabinet.

GEORGE WISE.
